UNITED STATES PATENT OFFICE.

CHARLES E. PRATT, OF BOSTON, MASSACHUSETTS, AND ALBERT E. WALTERS, OF HARTFORD, CONNECTICUT, ASSIGNORS TO THE POPE MANUFACTURING COMPANY, OF HARTFORD, CONNECTICUT.

VELOCIPED.

SPECIFICATION forming part of Letters Patent No. 310,540, dated January 6, 1885.

Application filed November 28, 1884. (No model.)

To all whom it may concern:

Be it known that we, CHARLES E. PRATT, of Boston, Massachusetts, and ALBERT E. WALTERS, of Hartford, Connecticut, have jointly 5 invented certain new and useful Improvements in Velocipedes, of which the following is a specification.

Our improvements relate to that class of velocipedes known as "tricycles," and more particularly to the driving mechanism of such velocipedes, though they are applicable to quadriycles and other velocipedes; and they are in the nature of improvements upon the devices shown and described in Letters Patent of the United States No. 284,782, dated September 11, 1884, in which is set forth a variable epicyclic speed and power gear combined with the driving mechanism of a tricycle.

The objects of our present improvements are to combine an epicyclic speed and power mechanism with the driving or crank shaft of a velocipede, to secure greater compactness and lightness in the mechanism, to provide a simple, convenient, effective means of actuating said mechanism which may be operated by the rider without change of position, and to furnish a speed and power mechanism readily applicable to any velocipede having a crank-shaft and chain-gear, or its equivalent, connecting said crank-shaft with the main shaft of the velocipede, and frame-work also connecting said shafts. The means by which we accomplish these objects will be apparent by the following description and the annexed drawings.

Figure 1 shows in elevation and vertical section the shafts and frame-work, a driving-wheel and one side of the frame of a tricycle containing our improvements applied in one form. Figs. 2 and 3 show in elevation parts of our improvements as seen from the opposite side to that shown in Fig. 1, on a larger scale. Fig. 4 shows in section, on the plane of the axis of the crank-shaft, our improved power-gear box. Fig. 5 shows in perspective one side of the middle or sprocket disk, and Fig. 6 shows the opposite side of the same in elevation. Fig. 7 shows in perspective the in-

terior of the outer click-bearing disk, R, the interior of which is shown in Fig. 2. Fig. 7 50 shows in elevation the inner side of the annular gear-disk U, the outer side of which is shown in Fig. 1.

A is the driving-wheel of the tricycle.

B is the main shaft.

C is the driving or crank shaft.

D is the sprocket-wheel or chain-wheel on the driving-shaft.

E is the chain connecting the sprocket-wheel D on the main shaft with the sprocket-disk F 60 on the driving-shaft C.

G is a part of the frame of a tricycle from which extends the arm H, which supports at one point the handle-rod I; and O is another part of the frame of a tricycle which supports 65 the bearing at one end of the crank-shaft C, and from which projects the arm L, supporting at another point the handle-rod I.

On the shaft C is fixed and revolving with it a disk, U, having at its periphery an inwardly-projecting lip in which is cut an annular gear, U'. On the shaft C, with a free bearing and capable of revolving thereon, we also place a sleeve, R', which bears at the end next the disk U a spur-wheel or concentric 75 gear, R'', and to the opposite end of which is threaded or otherwise fixed, to revolve therewith, a disk, R. Between the concentric gear R'' and the click-bearing disk R we place the sprocket-disk F, bearing the chain-teeth f f 80 on its periphery, which has a lip or flange to bring its teeth to the right position and support the chain passing over, and so is made to overlap the annular gear U', and which disk F has a free bearing toward its center at f' 85 upon the sleeve R', so that it is capable of revolving thereon. Between the sprocket-disk F and the fixed disk U we place intermediate gears or spur-wheels, T T, meshing with the annular gear U' and the concentric gear R'', 90 and mounted and free to turn upon pins or journals t t, set in and projecting from the sprocket-disk F. On the sprocket-disk F, on its side opposite the intermediate spur-wheels, is an annular projection, f', serving to give a 95 sufficient width of bearing on the sleeve R',

toward its center, and near its periphery are annular projections $f^2 f^2$, having between them the slots or notches f^3 , which, when the parts are in place, project into the disk R. The disk R, which is fastened to the sleeve R' toward its center, at r^2 , as above described, contains on the inner side, toward the sprocket-

f^3 , holding the disks R and F, and, consequently, the disk U, through the medium of the concentric gear R^2 , the annular gear U' , the intermediate gear, T T, and the axles $t t$, rigidly 70 together, and to the crank-shaft C, so that when the crank-shaft C is made to revolve by means of the pedal P the teeth $f f$ are made

practically or conveniently accessible to the rider when operating the tricycle.

We claim as new and of our invention—

- 5 1. The extensible lever Q N, constructed and adapted to operate essentially as set forth.
- 10 2. The bracket K, having means for attachment to the frame-work of a velocipede, a way to admit of movement of the lever, and means for holding the lever in one of two positions, essentially as set forth.
- 15 3. The adjustable detent k^4 , constructed and adapted to operate substantially as and for the purposes set forth.
- 20 4. The combination, in a velocipede, of lever-arm Q, bracket K, way k^2 , detent k^4 , and spring q , essentially as set forth.
- 25 5. The combination, in a velocipede, of bracket M, arm L, and the pivoted lever N, essentially as set forth.
- 30 6. In an epicyclic variable-speed mechanism, a click-arm, S, click s^2 , slide S' , and spring s^4 , constructed, combined, and adapted to operate essentially as set forth.
- 35 7. In an epicyclic variable-speed mechanism, a disk, F, having on one side projections f^2 and slots f^3 , and on the other side axles t^4 , or their equivalent, constructed and adapted to operate essentially as set forth.
- 40 8. In an epicyclic variable-speed gear mechanism, the combination of a fixed disk on a shaft bearing an annular gear at or near its periphery, a concentric spur-gear free on a

shaft, an intermediate gear meshing with said annular gear and said spur-gear, and axled upon a disk, a sleeve connecting said spur-gear, and a disk fixed thereon, a disk free to revolve on said sleeve and between the fixed disk upon the shaft and the fixed disk upon the sleeve, and bearing an axle for the intermediate gear, and having slots on its opposite side from said gear, and sprocket-teeth, or their equivalent, on its periphery, and a lever, S, click s^2 , slide S' , and spring s^4 , all constructed and adapted to operate essentially as set forth.

45 9. In combination with the frame of a velocipede and an epicyclic two-speed mechanism, the actuating-lever N Q, pivoted at one point to a connection with the frame of a tricycle, having a click, n , at the lower end and a handle, q , at the upper end, and constructed and combined to operate upon said epicyclic two-speed mechanism, on a crank-shaft, and to be operated by the hand of the rider near the handle of the velocipede, essentially as set forth.
